COMBINED RADIO RECEIVER AND AMPLIFIER

Kikuo Ohta, Osaka, and Masaaki Miyamoto and Shuhei Taguchi, Moriguchi, Japan, assignors to Matsushita Electric Industrial Co., Ltd., Osaka, Japan

Filed Feb. 13, 1973, Ser. No. 332,198

Claims priority, application Japan Aug. 29, 1972

Term of patent 14 years

Int. Cl. D14—03

U.S. Cl. D56—4 B

FIG. 1

FIG. 2

FIG. 1 is a front, top and right side perspective view of a combined radio receiver and amplifier showing our new design; and

FIG. 2 is a rear, bottom and right side perspective view; the left side being substantially a mirror image of the right side.

We claim:

The ornamental design for a combined radio receiver and amplifier, as shown and described.
